PROJECTILE SKIRT

Alfred F. Mardarello, Hoboken, N.J., assignor to the United States of America as represented by the Secretary of the Army

Filed June 3, 1965, Ser. No. 461,208

6 Claims. (Cl. 102—38)

The invention described herein may be manufactured and used by or for the Government for governmental purposes without the payment to me of any royalty thereon.

This invention relates to an improved projectile skirt. Skirts are attached to the base of a projectile for the purpose of enhancing the aerodynamic characteristics of the projectile by giving it what is commonly known in the art as a boattail effect. Increased projectile range with a given payload is thus realized. The skirt commonly used is a hollow contoured body fitted to the projectile to form a smooth streamlined missile. The high drag forces ordinarily indigenous to a flat base projectile are considerably reduced as a result of this streamlined configuration. This diminished drag effect makes the aforesaid increased range possible.

A projectile-skirt combination is ordinarily incorporated into a standard cartridge containing a propellant and primer therefor. The propellant surrounds the skirt and also fills the hollow cavity thereof. When the cartridge is suitably fired the propellant gases develop the high pressure necessary for launching the projectile. The interior of the skirt is materially subjected to the high pressures while the projectile traverses and exits the launcher barrel. Accordingly the skirt must be carefully designed to withstand these pressures, otherwise the skirt might rupture resulting in serious consequences. Due to the high pressure to which the skirts are subjected they are looked upon as pressure vessels with design factors governed accordingly. By this criterion the skirt is designed as a hollow shell with a uniform internal pressure. As those skilled in the pressure vessel art readily understand, this necessitates a thick walled heavy skirt. Additional weight is naturally given to the projectile. Since weight of projectile is a limiting factor in its design the weight of a given skirt is, likewise, limited. The added skirt weight shifts the center of gravity of the projectile toward its rear. The effect of this center of gravity shift is critical in that the projectile can become unstable in flight if the shift is too great. Hence the skirt must either be eliminated or made so short in length as to be virtually unnecessary in light of the small increase in range it would provide.

Aerodynamic drag forces are reduced as the length to diameter ratio of the projectile is increased. As noted above, the weight of a skirt which may be used with a given projectile depends upon the internal pressure it must withstand and the center of gravity shift which it imparts to the projectile. Since the length of the skirt is also dependent upon its weight it, of course, follows that the length to diameter ratio of any projectile-skirt combination is likewise dependent upon skirt weight.

In the above illustrations the payload weight of the projectile was considered constant. The heavy skirts could be slightly lengthened if the weight of the payload was reduced. However, this is rarely considered since a relatively greater volume of payload material must be removed to compensate for addition of a small volume of the much heavier skirt material. The increase of skirt length available by this approach could only provide a small increase of range while considerably reducing the payload effectiveness.

In summary, the existing projectile skirts are seriously limited in their applications and, for all practicable pur-

2

poses, a projectile designer has only two alternatives when considering whether or not to use a projectile-skirt combination—he may select a heavy, short skirt sufficiently strong to withstand the internal gas pressures; or he may use no skirt at all. The heavy, short skirt unduly optimizes the length diameter ratio available with any given projectile while seriously affecting payload weight. On the other hand eliminating the skirt altogether necessarily means that the range available to a given projectile is limited by the increased drag force effects on that projectile.

Accordingly, it is an object of the present invention to provide a projectile skirt which is lightweight and able to withstand the internal pressures engendered by burning propellant gases.

It is a further object of the present invention to provide a projectile skirt which can be formed from material the same as or different from that of the projectile to which it will be attached.

It is still another object of the present invention to provide a projectile skirt which can be manufactured as a separate element or integrally formed with a projectile.

It is yet another object of the present invention to provide a projectile skirt which is thin walled and lightweight and contains a plurality of longitudinally formed openings therethrough which openings allow a rapid release of propellant gases from the skirt cavity thereby resulting in pressure equalization on both sides of the skirt wall when the skirt is still within and exiting the launcher barrel.

The foregoing and other objects and advantages will become apparent from the following detailed description thereof, consideration being given also to the attached drawings in which:

FIG. 1 is a side elevation view partly fragmented showing an embodiment of the present invention;

FIG. 2 is a perspective view of FIG. 1 showing further details of construction;

FIG. 3 is a view of FIG. 1 showing same in an environmental setting;

FIG. 4 is a perspective view of the present invention showing another embodiment thereof.

Referring to the figures wherein like reference numerals refer to like parts 10 is a hollow skirt which is curvilinear in shape (frusto conical in this embodiment) having a restricted opening at its rear end. The skirt 10 is fixed to the rear end or base of a projectile 12. The skirt 10 may be secured to the projectile by any suitable means such as keying, threading, pressing, forcing, sweating or the like, so long as the two elements are rigidly fixed to each other to form a single continuous surface. The skirt 10 may also be formed as an integral part of a projectile 12 as shown in FIG. 4.

The skirt 10 is considerably thin walled with regard to the wall 14 of the projectile 12. This necessarily means that the weight of skirt per unit length is considerably less than that of the projectile 12. The significance of the thin walled skirt of this invention will be apparent from further reading of this specification.

The skirt 10 is provided with a plurality of openings longitudinally oriented along the wall of the skirt 10 and passing therethrough. In FIG. 1 the openings are shown as four slots 16 extending from the restricted rear end of the skirt 10 to a point midway along the surface thereof. The slots 16 are spaced ninety degrees apart in this embodiment. In FIG. 4 the openings are shown as holes 17, circular in shape and arranged in a regular pattern. The function of the openings of the skirt 10 are best understood by considering FIG. 3. In this illustration the projectile 12—skirt 10 combination is shown incorporated in a cartridge 18 containing a propellant mix 20 suitable for a desired application. The cartridge 18

and projectile-skirt arrangement is shown positioned in a launcher barrel 19 illustrated in phantom outline. The cartridge 18 contains a primer 22 for firing the propellant 20. The propellant 20 fills the greater portion of the cartridge 18 cavity and also surrounds the skirt 10 and fills the skirt cavity. When it is desired to fire the projectile 12-skirt 10 the primer 22 is initiated igniting the propellant 20. The ignited propellant 20 engenders a typical high pressure front for motivating the projectile out of the launcher. The cavity of the skirt 10 is naturally subjected to the high pressure while the projectile-skirt combination remains in the launcher barrel. The slots 16 allow the gases within the cavity of the skirt 10 to rapidly escape therethrough thus resulting in an equalization of gas pressure on either side of the skirt wall while the skirt is within and exiting the launcher barrel 19. It is to be understood that the gases will also escape through the skirt 10 rear open end. However, it has been found that an open ended skirt alone is inadequate to allow the entrapped gases to escape rapidly enough to result in equalization of pressure on both sides of the skirt wall.

The equalization of pressure on both sides of the skirt 10 wall permits the skirt 10 to have a wall thickness thinner than was normally used heretofore. The old art skirt walls had to be strong enough to withstand the high pressures within the skirt cavity. This naturally meant a thicker walled skirt as well as a skirt which was considerably heavier per unit length than is the skirt of the present invention. The advantages of the lightweight skirt have been pointed out earlier in this specification.

The embodiment shown in FIG. 3 shows a payload 24 within the projectile 12. The payload 24 may be any well known explosive or other agent suitable for a particular use. The effect of the old art heavy skirt on a payload has also been pointed out earlier in this specification, along with statements showing how a lightweight skirt 10 as that of this invention avoids the detrimental effect on the payload.

The openings through the skirt 10 wall, illustrated as slots 16 and holes 17 in FIG. 2 and FIG. 4 respectively, may take any shape and pattern in accordance with a particular application. The importance in selecting the type opening and the pattern thereof is that a suitable arrangement be selected so that a rapid escape of propellant gases be manifested in order that the gas pressure be equalized on both sides of the skirt 10 wall.

I claim:

1. The combination of a projectile, a propellant, means for firing the propellant, and a thin walled hollow contoured skirt secured to the rear of said projectile and defining a continuous curvilinear surface with the outer surface of said projectile, said skirt having a restricted opened rearward end and a predetermined pattern of openings through the skirt wall to provide an escape for propellant gases whereby pressure equalization on either side of the skirt wall may be effected.

2. The combination as set forth in claim 1 wherein the material of said projectile is the same as that of said skirt.

3. The combination as set forth in claim 1 wherein the material of said projectile is different from that of the skirt.

4. The combination as set forth in claim 1 wherein said skirt and said projectile are distinct from each other and said skirt is locked to said projectile by suitable means.

5. The combination as set forth in claim 1 wherein said skirt and said projectile are integral.

6. The combination of a projectile having a thick wall of dense material, a propellant, means for firing said propellant, and a skirt defining a hollow contoured member having a restricted opened rearward end and having a wall thinner than said projectile wall, said skirt being constructed from a material having a density less than that of said projectile and having a predetermined pattern of openings through the skirt wall to provide an escape for propellant gases whereby pressure equalization on either side of the skirt wall may be effected.
